UNITED STATES PATENT OFFICE.

GABRIEL P. B. HOYT, OF NEW YORK, N. Y.

ROTARY VALVE.

1,091,340.

Specification of Letters Patent. Patented Mar. 24, 1914.

Application filed January 9, 1912. Serial No. 670,215.

To all whom it may concern:

Be it known that I, GABRIEL P. B. HOYT, a citizen of the United States, and a resident of the city of New York, Jamaica, borough 5 of Queens, in the county of Queens and State of New York, have invented a new and Improved Rotary Valve, of which the following is a full, clear, and exact description.

10 The invention relates to internal combustion engines, and its object is to provide a new and improved rotary valve arranged to prevent binding of the parts and to allow free passage of the explosive mixture and 15 the exhaust gases without danger of leakage. For the purpose mentioned use is made of a cylindrical valve chamber having ports in its side and an opening in one end, a rotary valve fitting into the said chamber and having 20 a port adapted to register with the said valve chamber ports, the said rotary valve being split at its port, and an annular partition fixed in the said valve chamber and having 25 ports opposite the said valve chamber ports, the said partition being split intermediate its ports.

A practical embodiment of the invention is represented in the accompanying drawings forming a part of this specification, in 30 which similar characters of reference indicate corresponding parts in all the views.

Figure 1 is a cross section of the rotary valve as applied to a two-cylinder internal combustion engine; Fig. 2 is a perspective 35 view of the rotary valve; Fig. 3 is a like view of the partition; Fig. 4 is a sectional side elevation of the same; Fig. 5 is a similar view of the valve; and Figs. 6, 7, 8 and 9 are sectional plan views of the rotary valve 40 in different positions and as applied to the two cylinders of a four-cycle engine.

The improved rotary valve is applied to the upper ends of the cylinders A and A' of a 4-cycle engine, and in each of the cylinders A and A' is mounted to reciprocate a piston B connected by a pitman C with a crank arm D of the engine shaft E, it being understood that the crank arms D are arranged approximately opposite each other 50 on the engine shaft E. The upper or working ends of the cylinders A and A' are connected with an inlet valve F and an exhaust valve G, of which the valve F serves to control the admission of the explosive mixture 55 into the cylinders A and A', and the valve G serves to control the exhaust of the products

of combustion from the cylinders A and A'. The valves F and G are alike in construction so that it suffices to describe but one in detail.

Each of the valves F and G is provided with a cylindrical valve casing H provided in its side with ports H', H² leading to the upper or working chambers of the cylinders A and A', and the bottom of each valve 60 chamber H is provided with a central opening H³, of which the opening H³ of the valve F is connected with a source of gas supply while the opening H³ of the exhaust valve G leads to the outside for conducting the 65 products of combustion to a suitable place of discharge. In the said valve chamber H is a cylindrical rotary valve I open at the top and bottom and provided on its upper end with a radial arm I' extending inwardly 70 and secured to the upper end of a valve stem J provided at its lower end with a bevel gear wheel J' in mesh with a bevel gear wheel J² secured on a shaft K provided with a gear wheel K' in mesh with a gear wheel K² 75 secured on the engine shaft E. Thus when the engine is running a rotary motion is 80 transmitted by the gearing just described to the valve stem J so as to rotate the same and with it the rotary valve I. The rotary valve 85 I is provided in its side with a port I² adapted to register with the cylinder ports H', H² and the said valve I has its inner surface eccentric to the outer surface thereof, and the port I² is located at the thinnest 90 part of the valve, and is provided at this thinnest portion with a split I³, as plainly indicated in the drawings. Within the rotary valve I extends a cylindrical partition L having its outer and inner surfaces eccentric one relative to the other and both eccentric to the valve casing H. The partition L is provided with two ports L', L² arranged 95 opposite the cylinder ports H', H², and the partition L is provided with a split L³ intermediate the ports L', L², and this split L³ is at the thinnest portion of the partition L and is arranged intermediate the ports H', H².

When the engine is running the valve I of the admission valve F controls the admission of the explosive mixture to the cylinders A and A' at the time the port I² of the said valve registers with the corresponding ports H' and H² of the cylinders A and A', and in a like manner the valve I of the exhaust valve G controls the exhaust of

the products of combustion from the cylinders A and A' at the time the port I² of the said valve registers with the corresponding ports of the cylinders A and A'. When 5 the partition L becomes heated it expands and closes owing to the split L³, and a similar action takes place when the valve I becomes heated. Now, by reference to Figs. 6, 7, 8 and 9, it will be noticed that the 10 thicker portion of the valve I is approximately intermediate the ports H' and H² at the time the valve port I² is diametrically opposite and the ports H', H² are closed, and the pressure within the cylinder A or 15 A' exerted against the corresponding valve I of the admission valve F, or the exhaust valve G during both the compression and explosion strokes, is against the thick portions of the valve, and the valve is not liable 20 to be shifted and effectively closes the ports H' and H² during the said compression and explosion strokes. On further rotation of the valve I from the position shown in Fig. 6 the space between the partition L 25 and the valve I increases at a point between the ports H' and H² (see Figs. 7 and 8), so that the valve is free to rotate without danger of binding and a free connection is made between the port I² and the ports H' 30 and H².

The valve I of the admission valve F is in the position shown in Fig. 6 when the explosion takes place in the cylinder A and compression in the cylinder A', and as the 35 valve rotates in the direction of the arrow a' it assumes the position shown in Fig. 7 during the exhaust stroke of the cylinder A and the explosion in cylinder A'. The valve I next assumes the position shown in Fig. 40 8 during the suction in the cylinder A and exhaust in cylinder A', and, as shown in Fig. 9, the valve finally reaches the position during the compression in the cylinder A and the suction in the cylinder A', after 45 which the above-described operation is repeated. The valve I of the exhaust valve G assumes positions similar to those of the valve I of the admission valve F during the time mentioned so that further description 50 is not deemed necessary.

It is understood that when the port I² registers with the port H' or H² it also registers with the corresponding port L' or L² in the partition L to establish communication 55 between the opening H³ and the interior of the working end of the cylinder A or A' for the admission of the explosive mixture or exhaust of the products of combustion.

60 Each of the cylinders A and A' is provided a distance from the working chamber with a port N leading to a primary exhaust valve O for an initial discharge of the products of combustion from the cylinder A or 65 A' at the time the piston B nears the end

of its explosion stroke, as shown in Fig. 1. The primary exhaust valve O is provided with a rotary valve P secured on the stem J of the exhaust valve G to open and close the port N at the proper time so that a primary exhaust of the products of combustion takes place as above mentioned. 70

It is understood that by the arrangement described the valve I is free to expand or contract owing to its split I³ at the port I² without danger of binding in the valve casting H, and as the annular partition L is split it also is free to expand and contract relative to the valve I without binding the latter, and by arranging the eccentric surfaces of the valve I and partition L in the manner described leakage is prevented especially during the compression and explosion strokes of the pistons B in the cylinders A and A'. 80

Having thus described my invention, I claim as new and desire to secure by Letters Patent: 85

1. A rotary valve, comprising a valve chamber, a rotary split valve fitting into the 90 said chamber, and an annular split partition fixed in the valve chamber and surrounded by the said rotary split valve.

2. A rotary valve, comprising a cylindrical valve chamber having ports in its side and an opening in one end, a rotary valve fitting into the said chamber and having a port adapted to register with the said valve chamber ports, the said rotary valve being 95 split at its port, and an annular partition 100 fixed in the said valve chamber and having ports opposite the said valve chamber ports, the said partition being split intermediate its ports.

3. A rotary valve, comprising a cylindrical valve chamber having ports in its side and an opening in one end, a rotary valve fitting into the said chamber and having a port adapted to register with the said valve chamber ports, the said rotary valve being 105 split at its port, and an annular partition 110 fixed in the said valve chamber and having ports opposite the said valve chamber ports, the said partition being split intermediate 115 its ports, and the said partition having its inner and outer surfaces eccentric one relative to the other.

4. A rotary valve, comprising a cylindrical valve chamber having ports in its side and an opening in one end, a rotary valve 120 fitting into the said chamber and having a port adapted to register with the said valve chamber ports, the said rotary valve being split at its port, and an annular partition 125 fixed in the said valve chamber and having ports opposite the said valve chamber ports, the said partition being split intermediate 130 its ports, and the said partition having its inner and outer surfaces eccentric one relative to the other and eccentric relative to the 135

said valve chamber and the said rotary valve having its inner surface eccentric relative to the outer surface.

5. A rotary valve comprising a cylindrical valve chamber having ports in its side and an opening in one end, a rotary valve fitting into the said chamber and having a port adapted to register with the said valve chamber ports, the said rotary valve being 10 split at its port, and an annular partition fixed in the said valve chamber and having ports opposite the said valve chamber ports, the said partition being split intermediate its ports, and the said partition having its 15 inner and outer surfaces eccentric one relative to the other and eccentric relative to the said valve chamber, and the said rotary valve having its inner surface eccentric relative to the outer surface, the said rotary 20 valve being thinnest at its port.

6. A rotary valve, comprising a cylindrical valve chamber having ports in its side and an opening in one end, a rotary valve fitting into the said chamber and having a 25 port adapted to register with the said valve chamber ports, the said rotary valve being split at its port, and an annular partition fixed in the said valve chamber and having ports opposite the said valve chamber ports, 30 the said partition being split intermediate its ports, and the said partition having its inner and outer surfaces eccentric one relative to the other, the thinnest portion of the partition being intermediate its ports.

35 7. A rotary valve, comprising a cylindrical valve chamber having ports in its side and an opening in one end, a rotary valve

fitting into the said chamber and having a port adapted to register with the said valve chamber ports, the said rotary valve being 40 split at its port, and an annular partition fixed in the said valve chamber and having ports opposite the said valve chamber ports, the said partition being split intermediate its ports, and the said partition having its 45 inner and outer surfaces eccentric one relative to the other and eccentric relative to the said valve chamber, and the said rotary valve having its inner surface eccentric relative to the outer surface, the said 50 rotary valve being thinnest at its port and the said partition being thinnest intermediate its ports.

8. A rotary valve, comprising a cylindrical valve chamber having ports in its side 55 and an opening in one end, a rotary valve fitting into the said chamber and having a port adapted to register with the said valve chamber ports, the said rotary valve being split at its port, and an annular partition 60 fixed in the said valve chamber and having ports opposite the said valve chamber ports, the said partition being split intermediate its ports, the said partition being provided with an annular outwardly-extending flange 65 forming a seat for the said rotary valve.

In testimony whereof I have signed my name to this specification in the presence of two subscribing witnesses.
